UNITED STATES PATENT OFFICE.

JOHN M. KENNEDY, OF LOS ANGELES, CALIFORNIA, ASSIGNOR OF ONE-HALF TO WILLIAM H. HOEGEE, OF SAME PLACE.

DESIGN FOR A FLAG OR SIMILAR ARTICLE.

SPECIFICATION forming part of Design No. 29,053, dated July 19, 1898.

Application filed May 11, 1898. Serial No. 680,418. Term of patent 3½ years.

To all whom it may concern:

Be it known that I, JOHN M. KENNEDY, a citizen of the United States, residing at Los Angeles, in the county of Los Angeles and State of California, have invented and produced a new and original Design for a Flag or Similar Article, of which the following is a specification, reference being had to the accompanying drawing, showing the same.

10 My new design consists of a body strip or stripe A, having arranged therealong small sections of various shapes and colors different from the colors of the body-section, the various colors being indicated by difference 15 in shading, while the body-strip, where it appears, is left unshaded. Upon one or both sides of this body strip or stripe are arranged series of smaller stripes B C, the stripes alternating, and the stripes of one series being 20 of one color and the stripes of the other series

being white or of a color contrasting with the color of the first series, so that the stripes and the various sections forming the body-stripe will appear distinct and clear from each other.

25

The general form of the design is rectangular.

The characteristic features of the design comprise the body-stripe having arranged thereon sections of various sizes and colors 30 and the series of stripes of different colors arranged upon one or both sides of the body-stripe.

What I claim is—

35 The design for a flag or similar article, substantially as set forth.

JOHN M. KENNEDY.
